COMBINED CANDLE HOLDER AND CANDLE THEREFOR

Walter I. Bieger, Minneapolis, Minn., assignor to Arthur Salm Inc., Chicago, Ill., a corporation of Illinois

Continuation of design application Ser. No. 74,996, May 21, 1963. This application Feb. 12, 1965, Ser. No. 83,799

Term of patent 14 years

(Cl. D48—2)

FIG. 1 is a perspective view of a combined candle holder and candle therefor incorporating my new design;
FIG. 2 is a top plan view thereof; and

FIG. 3 is a side elevational view thereof.

This application is a continuation of my earlier pending application S.N. D.74,996 filed May 21, 1963, and now abandoned.

I claim:

The ornamental design for a combined candle holder and candle therefor, substantially as shown and described.
